(57) **CLAIM**

The ornamental design for an absorbent floor pad for pets as shown and described.

DESCRIPTION

FIG. 1 is a perspective view of the absorbent floor pad for pets.

FIG. 2 is a side view thereof. The other side view is identical to this side view and therefore the other side view is not shown.

FIG. 3 is a front view thereof. The back view is identical to this side view and therefore the back view is not shown; and, FIG. 4 is a top view thereof.

The evenly spaced dashed lines depict portions of the absorbent floor pad for pets that forms no part of the claimed design. The dot-dash broken lines in FIGS. 1 and 4 depict environmental subject matter only and forms no part of the claimed design.

1 Claim, 2 Drawing Sheets
